BASEBALL PROJECTING APPARATUS

Christopher T. Barron, Salem, N. H.

Application January 23, 1939, Serial No. 252,275

2 Claims. (Cl. 124—36)

This invention relates to apparatus for projecting baseballs in such a manner as to be useful for batting practice, and more particularly to that portion of the apparatus by which the ball is given a spin in one direction or another to impart a curve to its flight. It is an object of the invention to provide apparatus which is simple, effective and easy to operate and control.

According to the invention, a tube of suitable size is provided, from which a baseball can be projected by a blast of compressed air. Near the orifice of the tube the ball engages in passing a friction member which yieldingly projects into the bore of the tube from the wall thereof. This momentary retardation of one side of the ball just before it emerges from the tube imparts a spin to the ball, the rate and direction of the spin being controlled by adjustments of the friction member.

For a more complete understanding of the invention, reference may be had to the description thereof which follows, and to the drawing of which.

Figure 1 is a side elevation of apparatus embodying the invention.

Figure 2 is a sectional view on a larger scale, taken on the line 2—2 of Figure 1.

Figure 3 is a sectional view of a modified form of the apparatus shown in Figure 2.

Figure 4 is a section on the line 4—4 of Figure 3.

As shown in Figure 1, apparatus for projecting baseballs for batting practice or other purposes may consist primarily of a tube 10 which is mounted above an elongated tank 12 of suitable capacity, and communicates therewith through a pipe connection 14 in which is a control valve 16 operated by a handle 18. Near the valve 16 is a suitable aperture 20 in the tube. A sleeve 22 is slidably fitted on the tube and is movable to cover the aperture 20 so as to prevent excessive escape of air admitted to the tube through the valve 16. The tank is provided with an inlet 24, preferably having a check valve (not shown), this inlet being connected, when the tank is in use, to a suitable compressor pump by a flexible tube, the pump and tube not being shown. The tank 12 and tube 10 are assembled as a single unit, the forward end portions of the tank and tube being rigidly connected by a suitable element 26, the rear end portions being rigidly connected by the pipe 14.

For pointing and training the tube 10, the tank and tube are pivotally mounted for angular adjustment as a unit about horizontal and ver-

tical axes. To this end the tank 12 may be mounted on suitable trunnions as at 30, these trunnions being carried by a yoke 32 pivotally mounted as at 34 on a pedestal 36. Projecting rearwardly from the pedestal 36 is a sector plate 38 having an arcuate slot through which projects an elevating screw 42. On the elevating screw are a pair of nuts 44 and 46 by which the tube 10 may be secured in any position of adjustment.

In using the projecting apparatus, a baseball may be dropped into the tube through the aperture 20, the aperture then being closed by sliding the sleeve 22 over it. Air may be pumped into the tank through the inlet 24 until the desired pressure as indicated on a suitable gage 50 is obtained. Thereupon the handle 18 is manipulated to open the valve 16, allowing the compressed air in the tank 12 to discharge through the tube 10, impelling the baseball therefrom. The initial velocity of the baseball as it leaves the tube can be regulated by the amount of air pressure accumulated in the tank prior to the opening of the valve 16.

Since it is usually desirable to impart more or less of a spin to the ball as it leaves the tube in order to curve its trajectory in one way or another imitating the various curves employed by baseball pitchers, a suitable attachment is provided which may be removably secured to the discharge end of the tube or may be a permanent part of the tube itself. As shown, this attachment consists of a tubular member 60 having a sleeve portion 62 adapted to fit snugly on the end portion of the tube 10. The member 60 also has a portion 64 with a bore equal to that of the tube 10 so that the portion 64 of the tubular member is virtually an extension of the tube itself, its bore being aligned with and forming a continuation of the bore of the tube 10. At one side of the portion 64 is a yieldable friction element 66 which, as illustrated in Figure 2, may be the rounded end portion of the plunger 68 which projects through the wall of the tubular member 60, the rounded end portion 66 being arranged to project into the bore of the extension 64. The plunger 68 is provided with an intermediate flange 70 which normally bears against the outer surface of the member 60 so as to limit the extent of projection of the friction element 66 into the bore. The outer portion of the plunger 68 extends slidably through a thimble 72 which is threaded into a supporting bracket 74, the latter being secured to the member 60 by suitable screws 76. Between the

flange 70 and the thimble 72 is a compression spring 80 which serves to press the friction element 66 inward toward the axis of the tube 10. The spring 80, however, permits the element 66 to yield radially outward so that its end may be flush with the inner surface of the member 60. When a baseball 82 is projected from the tube 10, one side thereof will engage and be retarded by the friction element 66. This will cause the ball to rotate as indicated by the arrow in Figure 2 as it leaves the tube. The spin thus produced will result in a curving of the path of the ball in a manner well known. In order to produce the various kinds of curves employed by baseball pitchers, the attachment 60 is preferably adjustable angularly about the axis of the tube. Since the sleeve portion 62 is cylindrical, it is readily slidable on the end portion of the tube 10 to alter the angular position of the member 60 on the tube. In order to secure the member 60 in any desired position of angular adjustment, a setscrew 84 is provided. This setscrew is threaded through the sleeve portion 62 of the member 60, the inner end of the screw 84 projecting into a groove 86 which extends around the end portion of the tube 10 and is located so as to prevent the attachment 60 from coming off the end of the tube 10 unless the setscrew 84 is backed off sufficiently to clear the groove 86.

Ordinarily, the screw 84 is loosed sufficiently to permit rotational adjustment of the member 60. After such adjustment has been made, the screw is set up again so as to bind against the bottom of the groove 86 and thus to hold the member 60 in adjusted position. The screw may have a thumb piece 88 at its end for convenient manipulation, and, if desired, a lock nut 90 may also be provided thereon.

The friction device for imparting spin to the baseball may be made in other ways such as that illustrated in Figures 3 and 4. As therein shown, the frictional element may comprise a strip 92 of suitable friction material, such as brake band lining for example, this strip being secured to a strip 94 of metal. This composite strip is disposed in a longitudinal groove 96 in the wall of the extension 64, the groove 96 being of sufficient depth to receive the composite strip so that the latter is flush with the interior surface of the

tube 10. The inner end of the strip is secured in the groove 96 by a screw 98 or by other suitable means. The outer end of the strip is attached to a plunger 100 which may be somewhat similar to the plunger 68 illustrated in Figure 2. Similar means, such as a thimble 72 threaded into a bracket 114, and a spring 80, may be employed to press the plunger 100 inward so as to hold the outer end of the friction strip within the bore of the projecting portion 64 of the attachment 60. Thus a baseball 82 traveling along the tube 10 engages the friction strip 92. The engaging side of the ball 82 is thus retarded as the ball reaches the orifice of the tube extension 64, imparting a spin to the ball. The amount of spin of the ball and the resulting "break" of the curve can be controlled by adjusting the compression of the spring 80 by means of the thimble 72.

It is evident that various modifications and changes may be made in the specific embodiments of the invention herein illustrated and described without departing from the spirit or scope thereof as defined in the following claims.

I claim:

1. In an apparatus including a tube for projecting a baseball, a device for imparting a spin to the ball, said device comprising a plunger having a rounded inner end projecting into the bore of the tube near the discharge end thereof and yieldable radially away from the axis of the tube, a spring pressing said plunger inward, and means for adjusting the pressures of said spring.
2. In an apparatus including a tube for projecting a baseball, a tubular extension on the discharge end of said tube, said extension having a bore forming a continuation of the bore of the tube, means for securing said extension to said tube in any position of angular adjustment about the axis of the tube, a plunger projecting radially through the wall of said extension and into said bore, the inner end of said plunger being rounded, means limiting the inward movement of said plunger, spring means yieldably pressing said plunger inward against said limiting means, and means for adjusting the force of said spring means.

CHRISTOPHER T. BARRON.
